DESIGN FOR A COMBINATION LIGHT FIXTURE AND ORNAMENT HOLDER

Frank I. Szalla, Chicago, Ill.

Application October 23, 1942, Serial No. 108,604

Term of patent 14 years

To all whom it may concern:

Be it known that I, Frank I. Szalla, a citizen of the United States and residing in Chicago, in the county of Cook and State of Illinois, have invented a new, original, and ornamental Design for a Combination Light Fixture and Ornament Holder, of which the following is the specification, reference being had to the accompanying drawing, forming a part thereof.

On the drawing:

Fig. 1 is a front elevational view of a combination light fixture and ornamental holder showing my new design;

Fig. 2 is a rear elevational view;

Fig. 3 is a bottom plan view;

Fig. 4 is a top plan view; and

Fig. 5 is a side elevational view thereof.

I claim:

The ornamental design for a combination light fixture and ornament holder, substantially as shown.

FRANK I. SZALLA.
